UNITED STATES PATENT OFFICE.

HARRY J. BOSWORTH, OF CHICAGO, ILLINOIS.

DESIGN FOR AN ASEPTIC STAND.

52,778.

Specification for Design.

Patented Dec. 24, 1918.

Application filed January 21, 1918. Serial No. 213,079. Term of patent 14 years.

To all whom it may concern:

Be it known that I, HARRY J. BOSWORTH, a citizen of the United States, residing at Chicago, in the county of Cook and State of Illinois, have invented a new, original, and ornamental Design for Aseptic Stands, of which the following is a specification, reference being had to the accompanying drawing, forming a part thereof.

The figure is a perspective view of an aseptic stand showing my new design.

I claim:

The ornamental design for an aseptic stand as shown.

HARRY J. BOSWORTH.
